[57] CLAIM

The ornamental design for a sprayer head, substantially as shown and described.

DESCRIPTION

FIG. 1 is a top plan view of a sprayer head showing my new design;

FIG. 2 is a side elevation thereof;

FIG. 3 is an opposite side elevation thereof;

FIG. 4 is a front elevation thereof; and

FIG. 5 is a rear elevation thereof.

The broken-line showing of a container in FIGS. 1-3 is for illustrative purposes only and forms no part of the claimed design.

FIG. 1

FIG. 2

FIG. 3

FIG. 4

FIG. 5
